CONVERSION OF HYDROCARBON OILS

Louis C. Rubin, Nutley, N. J., assignor to Gasoline Products Company, Inc., Newark, N. J., a corporation of Delaware

Application April 22, 1936, Serial No. 75,663

5 Claims. (Cl. 196—49)

This invention relates to a method of processing hydrocarbon oil and pertains more particularly to a method of treating raw crude oil, partially reduced crude or other heavy stock of comparable characteristics to produce a maximum yield of high anti-knock gasoline.

It is generally understood in the art that cracking stock recovered by the initial distillation or mild cracking treatment of crude oil is better suited for high-temperature extensive cracking operations essential to the production of high anti-knock gasoline than intermediate cycle stock resulting from extensive cracking. In view of this, in the treatment of raw crude oil or the like to produce gasoline it has been a practice to first subject the crude oil to distillation to vaporize and separate from the remaining residue all vaporizable constituents above the gasoline boiling range which are amenable to high temperature, high crack per pass cracking treatment which will produce desirably high anti-knock gasoline. It has also been a practice to subject the residue resulting from this initial distillation to cracking treatment.

Due to the coke-forming character of this stock, however, the cracking treatment must be carried out at a relatively low temperature unsuited for production of high anti-knock gasoline. The principal reason for cracking this type of stock is to form additional quantities of lighter hydrocarbons which in turn may be subjected to high-temperature drastic cracking conditions which will produce a further yield of high-grade gasoline.

It is an object of my invention to provide a method of processing hydrocarbon oil so as to recover from the original crude stock or the like a maximum yield of charging stock which may be treated under conditions favorable to the formation of high anti-knock gasoline and to subject the charging stock so recovered from the crude oil to conditions which will produce as a final product a high-grade gasoline.

Another object of my invention is to provide a method of processing heavy oil such as crude or topped crude oil wherein the individual steps of the process are carried out in such relation to each other as to improve the over-all efficiency of the operation.

Other and more specific objects of my invention will become apparent from the more detailed description hereinafter. The above and other objects will be obtained by certain novel steps and combination of steps constituting my invention which will now be described.

In accordance with my invention a crude oil, or an oil stock containing a preponderance of virgin constituents is initially distilled to remove the lower-boiling constituents therefrom. The residue resulting from this initial distillation is subjected to mild cracking treatment principally for producing an intermediate charging stock which is subsequently subjected to drastic cracking treatment as hereinafter described. The products from this mild cracking treatment are thereafter removed into a distilling chamber in admixture with a light gaseous stock such as products from a reforming operation which will aid in the distillation of the products and liberate therefrom all constituents which are amenable to high temperature, high crack per pass cracking conditions and result in a final residual product of heavy viscous nature.

The vapors resulting from this distillation are then fractionally separated into a heavy condensate, a light intermediate condensate and a final distillate product.

The heavy condensate so separated is then subjected to independent cracking treatment under relatively mild conditions to form additional light condensate which is amenable to high temperature, high crack per pass cracking treatment. The products from this mild cracking treatment are thereafter introduced into the first-mentioned distilling chamber and subjected to distillation along with the products from the initial cracking treatment hereinbefore described.

The light condensate so separated is subjected to high temperature, high crack per pass vapor-phase cracking conditions suitable for the production of a maximum quantity of high anti-knock gasoline and thereafter introduced into a separate evaporator in which vapors and residues separate. The vapors thereof are subjected to further fractionation to separate insufficiently converted products of reflux condensate and a final distillate product of the desired end point.

The insufficiently converted condensate formed as a result of the last-mentioned fractionation is then returned to the vapor-phase cracking coil and subjected to further cracking treatment along with the light condensate resulting from the initial mild cracking treatment hereinbefore described.

A heavy naphtha fraction resulting from the fractionation of the original crude and a fractionation of the vapors from the mild distilling chamber is in turn passed through a heating coil and subjected to reforming conditions suit-

able for improving the anti-knock properties thereof a desired amount and the products from the reforming coil thereafter combined with the products resulting from the initial mild cracking treatment prior to their introduction into the distilling chamber.

Having described the general nature and objects of my invention I will now proceed with a more specific detailed description thereof in which reference will be made to the accompanying drawing which is a diagrammatic and simplified illustration of an apparatus suitable for carrying the invention into effect.

The apparatus may comprise in general the combined crude distilling and fractionating tower 10, a low-temperature cracking furnace 11, a combined low-pressure vapor separator and fractionating tower 12, a fractionating tower 13 connected therewith, a high-temperature furnace 14, a separating chamber 15 connected therewith, a fractionating tower 16 associated with said reaction chamber together with the necessary pipe lines, valves, controls, heat exchangers and other appurtenant equipment for carrying out the process as hereinafter described.

Fresh charging oil, which may comprise crude, topped crude or similar stock having lighter and heavier constituents, after preliminary heating to a distilling temperature, for example, by indirect heat exchange with hot products resulting from the subsequent cracking steps or after having been heated in a directly-fired coil, or both, is forced through charging line 20 by means of pump 21 to the bottom section of the combined crude-distilling and fractionating tower 10 wherein the crude oil is subjected to distillation. Vapors liberated as a result of the distillation in the bottom section of the tower 10 pass upwardly through trap-out tray 23 and are subjected to fractionation in the intermediate section 24 of the tower. Condensate resulting from the fractionation in the intermediate section 24 of the tower 10 collects in trap-out tray 23 and may be withdrawn therefrom through line 25 and subjected to further cracking treatment as hereinafter described. This condensate may have an initial boiling point of from 400° to 500° F., for example, and an end point of about 650° F. Vapors remaining uncondensed in the intermediate section 24 of the tower 10 pass upwardly through trap-out tray 26 and are subjected to fractionation thereabove to condense heavy naphtha constituents thereof. Condensate formed in the upper portion of the tower 10 collects in trap-out tray 26 and is withdrawn therefrom through line 27 and subjected to further treatment as hereinafter described. This condensate may have an initial boiling point of from 200° to 300° F. and an end point of from 400° to 500° F. Vapors remaining uncondensed in the upper portion of the tower 10 pass upwardly through line 28 to condenser 29 wherein the light naphtha constituents of the original charging stock are condensed. The condenser 29 discharges into receiving drum 30 wherein the final distillate separates from gases. Gases are removed from receiving drum 30 through line 31 and the desired light naphtha distillate through line 32.

Residue resulting from the distillation of the original charging stock in the bottom portion of the tower 10 is withdrawn therefrom through line 33 and is forced by means of pump 34 through heating coil 35 located in the low-temperature furnace 11. The oil, during its passage through the heating coil 35, is subjected to mild cracking

conditions for the purpose of forming intermediate cycle stock which is amenable to high-temperature cracking treatment. The products from the heating coil 35 may be passed directly through line 36 to the lower section of the combined separating and fractionating tower 12 or they may be passed through line 37 to a reaction chamber 38 wherein the desired conversion may be carried to completion. In such case the products from the reaction chamber 38 are withdrawn therefrom through line 39 which merges with line 36 and are conveyed to the tower 12 as hereinbefore described. Products from the heating coil 35, or from the reaction chamber 38, upon being introduced into the bottom section of the tower 12 are subjected to drastic distillation to vaporize all distillable fractions therefrom and produce a heavy viscous residue. In order to effect this desired drastic distillation the products from the heating coil 35 are merged with lighter gaseous products before being introduced into the chamber 12. These gaseous products are preferably products obtained from the reforming of the heavy naphtha constituents as hereinafter described. Residue resulting from the drastic distillation of the products from the heating coil 35 or the reaction chamber 38 are withdrawn from the bottom of tower 12 through line 40 and are cooled and passed to storage or subjected to further treatment as desired.

Vapors resulting from the distillation in the bottom of the tower 12 pass upwardly through trap-out tray 41 located therein and are subjected to initial fractionation in the upper section thereof. Heavy condensate formed in the upper section of the tower 12 collects in trap-out tray 41 and is withdrawn therefrom through line 42. This heavy condensate may have an initial boiling point of above 650° F., for example. Condensate withdrawn from trap-out tray 41 is returned via line 42 to a second heating coil 43 located in the low-temperature furnace 11 wherein it is subjected to further mild cracking treatment to form lighter constituents amenable to high-temperature treatment. Products from the heating coil 43 are discharged through transfer line 44 and may be passed through lines 45 and 37 to the reaction chamber 38 with products from the heating coil 35, or the products may be introduced into the transfer line 36 wherein they combine with the products from the heating coil 35.

Vapors remaining uncondensed in the upper section of the tower 12 pass over therefrom through line 47 to fractionating tower 13 wherein they are subjected to further condensation to separate a light intermediate fraction. This fraction may have, for example, an initial boiling point of from 400° to 500° F. and an end point of about 650° F. Condensate formed in the lower portion of the tower 13 is withdrawn therefrom through line 48 and is merged with condensate formed in the intermediate section of the crude distilling chamber 10 and withdrawn therefrom through line 25.

The fractionating tower 13 may be provided with a trap-out tray 49 and positioned to collect heavy naphtha constituents of the vapors, or the fractionating tower 13 may be regulated to take overhead a distillate of the desired end point. Vapors remaining uncondensed in the tower 13 pass overhead through line 51 to a condenser 52 wherein gasoline constituents thereof are condensed. Condenser 52 discharges through line 54 to a receiver 55 wherein gases and distillate separate. Distillate is withdrawn from receiver 75

55 through line 56, and gases are vented through pipe 57 provided with valve 58 for maintaining the desired back pressure on the fractionating tower 13.

5 Combined condensate from the bottom of fractionating tower 13 and the trap-out tray 23 continues through line 48 and is forced by means of pump 59 through heating coil 61 located in the high-temperature furnace 14. The oil, during its 10 passage through the heating coil 61, is subjected to high temperature, high crack per pass conditions to effect maximum conversion into gasoline of high anti-knock properties. Products from the heating coil 61 discharge through transfer line 62 to separating chamber 15, wherein vapors and residue separate. Residue from the tower 15 is withdrawn through line 63 and may be cooled and withdrawn from the system or subjected to further treatment as desired. Vapors 15 liberated in the separating chamber 15 pass overhead through line 64 to fractionating tower 16 wherein they are subjected to fractionation to condense insufficiently converted constituents therefrom. Condensate resulting from the fractionation in tower 16 is withdrawn from the bottom thereof through line 65 and is returned to line 48 for further treatment in the heating coil 61.

Vapors remaining uncondensed in the fractionating tower 16 pass overhead through line 66 to condenser 67 wherein the desired distillate condenses. Condenser 67 discharges to a receiving drum 68 wherein gases and distillate separate. Gases pass overhead through line 69 and are 20 withdrawn from the system and the distillate is removed from the system through line 71.

Heavy naphtha constituents resulting from the distillation of the crude oil in tower 10 and collected on trap-out tray 26 are withdrawn through line 27 and passed by means of pump 72 to a second heating coil 73 located in the high-temperature furnace 14 wherein they are subjected to reforming conditions of temperature and pressure. Products from the reforming coil 73 discharge through line 74, and all or part thereof are passed through line 75 to transfer line 36 wherein they merge with products therein and aid in the distillation of the heavy products as hereinbefore described. A portion of the 25 reformed products of the heating coil 73 may be passed via line 76 to the separating chamber 15. If desired light stripping gas from an extraneous source may be introduced into transfer line 36 through line 77 to serve as a stripping medium during distillation of the products in the bottom of tower 12. Such gas may be uncondensed gas from receiving drums 30, 55 or 68.

Having described the general combination of steps and sequence thereof constituting my invention, the following example may be helpful in carrying out my invention to obtain the greatest advantages therefrom, it being understood that the values given herein are illustrative rather than limitative. For example, the original crude oil, which may be any of common crude oils, such as Mid-Continent crude, is initially heated to a distilling temperature of from 600° to 700° F. or thereabout before being discharged into the distilling and fractionating chamber 10. The distillation of the crude charge in the tower 10 may be controlled to vaporize all constituents boiling below 650° to 750° F. Unvaporized reduced crude stock from the bottom of the tower 10 having an initial boiling point of from 650° to 700° F. or thereabout may be heated to an out-

let temperature of from 875° to 900° F. during its passage through the heating coil 35 provided the time of treatment is limited to avoid excessive coke deposition. The temperature and time of treatment of the reduced crude in the heating coil 35 or the heating coil 35 and reaction chamber 38 may be regulated with respect to each other to produce from 20 to 30% of constituents boiling below the initial boiling point of the reduced crude of which from 8 to 15% thereof may 10 boil within the range of gasoline.

The products from the heating coil 35 or from the reaction chamber 38, as the case may be, after being introduced through the bottom section of the separating and fractionating tower 12 are subjected to distillation to remove all distillable fractions therefrom and form a heavy residual product having, for example, a viscosity measurement of above 3000 seconds at 122° F. as measured by a Saybolt Furrol viscosimeter.

Heavy condensate collected in the trap-out tray 41 of the tower 12 may have an initial boiling point of above 600° F. This condensate, during its passage through the heating coil 43, may be heated to a temperature ranging from about 850° to 925° F., for example, and for a time sufficient to effect from 10 to 20% thereof into gasoline constituents. The oil, during its passage through the heating coil 43, is preferably maintained under relatively high pressure, such as a 20 pressure in excess of 400 pounds per square inch.

Condensate collected in the bottom of fractionating tower 13 may have an initial boiling point ranging from about 250° to 500° F. and an end point of 650° F. This fraction, combined with the fraction taken from trap-out tray 23 of the crude distilling tower 10 during its passage through heating coil 61 may be subjected to a temperature ranging from 850° to 1050° F. or more and subjected to cracking conditions and temperatures for a time adequate to effect to from 20 to 40% or more into gasoline constituents.

The heavy naphtha fraction separated from the original crude stock in the initial distilling zone 10 in trap-out tray 26 and, if desired, the heavy naphtha constituents separated in the fractionating tower 13 may be subjected to a temperature ranging from 950° to 1100° F. during their passage through the heating coil 73.

The pressure maintained on different parts of the equipment is not critical to my process and may vary over a wide range depending on the nature of stock treated, character of the final products desired and other factors. In general the outlet pressures of the heating coils and the cracking portion of the equipment are materially higher than that maintained on the distilling and fractionating chambers. The outlet pressure on the heating coils may range, for example, from 300 to 1000 pounds or more per square inch. In practice it is usually preferred to carry higher pressures on coils 61 and 73 located in the high-temperature furnace 14 than are carried on coils 35 and 43 in the low-temperature furnace 11 in order to reduce gas loss. The pressure on heating coils 61 and 73 may range from 500 to 1000 pounds per square inch, and the outlet pressure on heating coils 35 and 43 may range from 300 to 500 pounds per square inch.

The pressure on the crude distilling tower 10, 70 the distilling tower 12 and fractionating tower 13 is preferably materially lower and may range from sub-atmospheric to about 300 pounds per square inch. The pressure on the separator 15 and fractionating tower 16 may be somewhat 75

higher, such as from 200 to 500 pounds per square inch.

While the above conditions of temperature, pressure and conversion per pass are given as an aid in operating the invention, it will be understood that the conditions may vary widely depending upon the character of the original stock and the character of the desired end products.

Having described the preferred embodiment of my invention it will be understood that it embraces such other modifications and variations as fall within the spirit and scope thereof and that it is not my intention to unnecessarily limit the invention or dedicate any novel features thereof.

15 15 I claim:

1. In the cracking of hydrocarbon oils, the process that comprises subjecting crude petroleum residuum to cracking in a primary viscosity-breaking zone under conditions to effect conversion

20 into a high yield of gas oil constituents, directing the resultant viscosity-broken products into a first separating zone wherein vapors separate from residue, passing the separated vapors to a first fractionating zone wherein the vapors

25 are subjected to fractionation to form therein a heavy gas oil fraction, a lighter gas oil fraction, a heavy naphtha fraction and a final gasoline distillate, subjecting the heavy gas oil fraction to cracking temperature in a secondary viscosity-breaking zone under conditions to effect conversion

30 into a high yield of lighter gas oil constituents, directing the resultant viscosity-broken products into said first separating zone, subjecting said lighter gas oil fraction to cracking temperature in a separate cracking zone under conditions of high cracking per pass to effect conversion into gasoline of high anti-knock quality, directing the resultant cracked products into a second separating zone wherein vapors separate

35 from residue, fractionating the separated vapors in a second fractionating zone to recover the desired high anti-knock gasoline product, subjecting aforesaid heavy naphtha fraction to cracking temperature in a separate reforming zone under conditions adequate to effect reforming of the gasoline constituents into constituents of increased anti-knock quality and directing the hot products of the reforming into said first separating zone.

40 50 2. In the cracking of hydrocarbon oils, the process that comprises subjecting crude petroleum to distillation to separate out a crude residuum, a gas oil fraction and a naphtha fraction, subjecting said crude residuum to cracking in a primary viscosity-breaking zone under conditions to effect conversion into a high yield of gas oil constituents, directing the resultant viscosity-broken products into a first separating zone wherein vapors separate from residue, passing the separated vapors to a first fractionating zone wherein the vapors are subjected to fractionation to form therein a heavy gas oil fraction, a lighter gas oil fraction, a heavy naphtha fraction and a final gasoline distillate subjecting the heavy gas

45 55 60 oil fraction to cracking temperature in a secondary viscosity-breaking zone under conditions to effect conversion into a high yield of lighter gas oil constituents, directing the resultant viscosity-broken products into said first separating zone, combining said lighter gas oil fraction with the gas oil fraction obtained from the crude distillation and subjecting the combined gas oil constituents to cracking temperature in a separate cracking zone under conditions of high cracking per pass to effect conversion into gasoline of high

65 70 75

60 65 70 75

65 70 75

70 75

anti-knock quality, directing the resultant cracked products into a second separating zone wherein vapors separate from residue, fractionating the separated vapors in a second fractionating zone to recover the desired high anti-knock gasoline product, combining aforesaid heavy naphtha fraction with the naphtha fraction obtained from the crude distillation and subjecting the combined naphtha fractions to cracking temperature in a separate reforming zone under conditions adequate to effect reforming of the gasoline constituents into constituents of increased anti-knock quality and directing the hot products of the reforming into said first separating zone.

3. In the cracking of hydrocarbon oils, the process that comprises subjecting crude petroleum to distillation to separate out a crude residuum, a gas oil fraction and a naphtha fraction, subjecting said crude residuum to cracking in a primary viscosity-breaking zone under conditions to effect conversion into a high yield of gas oil constituents, directing the resultant viscosity-broken products into a first separating zone wherein vapors separate from residue, withdrawing said residue from the process, passing the separated vapors to a first fractionating zone wherein the vapors are subjected to fractionation to form therein a heavy gas oil fraction, a lighter gas oil fraction and a final gasoline distillate, subjecting the heavy gas oil fraction to cracking temperature in a secondary viscosity-breaking zone under conditions to effect conversion into a high yield of lighter gas oil constituents, directing the resultant viscosity-broken products into said first separating zone, wherein vapors separate from residue, combining said lighter gas oil fraction with the gas oil fraction obtained from the crude distillation and subjecting the combined gas oil constituents to cracking temperature in a separate cracking zone under conditions of high cracking per pass to effect conversion into gasoline of high anti-knock quality, directing the resultant cracked products into a second separating zone wherein vapors separate from residue, fractionating the separated vapors in a second fractionating zone to recover the desired high anti-knock gasoline product, subjecting aforesaid naphtha fraction from the crude distillation to cracking temperature in a separate reforming zone under conditions adequate to effect reforming of the gasoline constituents into constituents of increased anti-knock quality and directing the hot products of the reforming into said first separating zone.

4. In the cracking of hydrocarbon oils, the process that comprises subjecting crude petroleum to distillation to separate out a crude residuum and a condensate, subjecting said crude residuum to cracking in a primary viscosity-breaking zone under conditions to effect conversion into a high yield of gas oil constituents, directing the resultant viscosity-broken products into a first separating zone wherein vapors separate from residue, passing the separated vapors to a first fractionating zone wherein the vapors are subjected to fractionation to form a heavy condensate and a lighter fraction, subjecting said heavy condensate to cracking temperature in a secondary viscosity-breaking zone under conditions to effect conversion into a high yield of lighter gas oil constituents, directing the resultant viscosity-broken products into said first separating zone, combining said lighter fraction with said condensate obtained from the crude distillation and passing the combined oils to a recycling cracking zone wherein the oil is subjected to

cracking temperature at superatmospheric pressure under conditions of high cracking per pass to effect conversion into gasoline of high anti-knock quality, directing the resultant products from said recycling cracking zone to a separate separating zone wherein separation of vapors from residue takes place, passing the separated vapors to a separate fractionating zone and subjecting them to fractionation therein to separate 10 a reflux condensate from lighter products and cycling said reflux condensate to the recycling cracking zone.

5. In the cracking of hydrocarbon oils, the process that comprises primarily separating crude petroleum into vapors and residue and fractionating the separated vapors to form a gas oil fraction and a naphtha fraction, subjecting resultant crude residue to cracking in a primary viscosity-breaking zone under conditions to effect conversion into a high yield of gas oil constituents, directing the resultant viscosity-broken products into a first separating zone wherein vapors separate from residue, passing the separated vapors to a first fractionating zone wherein the vapors 20 are subjected to fractionation to form a heavy condensate, a lighter gas oil condensate and a naphtha fraction, subjecting said heavy condensate to cracking temperature in a secondary viscosity-breaking zone under conditions to effect

conversion into a high yield of lighter gas oil constituents, directing the resultant viscosity-broken products into said first separating zone, combining said gas oil condensates obtained from the crude distillation and from said first separating zone and passing the combined oils to a separate cracking zone wherein the oil is subjected to cracking temperature at superatmospheric pressure under conditions of high cracking per pass to effect conversion into gasoline of 10 high anti-knock quality, directing the resultant products from said separate cracking zone to a second separating zone wherein separation of vapors from residue takes place, passing the separated vapors to a separate fractionating zone and 15 subjecting them to fractionation therein to separate a reflux condensate from lighter products, cycling said reflux condensate to said separate cracking zone, combining said naphtha fractions obtained from the crude distillation and from 20 said first fractionating zone and subjecting the naphtha mixture to cracking temperature in a separate reforming zone under conditions adequate to effect reforming of the gasoline constituents into constituents of increased anti-knock 25 quality and directing the hot products of reforming into said first separating zone.

LOUIS C. RUBIN.
